UNITED STATES PATENT OFFICE.

EDWIN MILLER, OF TAUNTON, MASSACHUSETTS.

COLLAR-FASTENER.

1,212,088.

Specification of Letters Patent.

Patented Jan. 9, 1917.

Application filed May 1, 1915. Serial No. 25,211.

To all whom it may concern:

Be it known that I, EDWIN MILLER, a citizen of the United States, residing at Taunton, in the county of Bristol and State 5 of Massachusetts, have invented certain new and useful Improvements in Collar-Fasteners; and I do hereby declare the following to be a full, clear, and exact description of the invention, such as will enable others 10 skilled in the art to which it appertains to make and use the same.

The invention relates to improvements in collar fasteners.

The object of the present invention is to 15 improve the construction of collar fasteners and to provide a simple, practical and inexpensive construction designed to be applied to an ordinary shirt at the back thereof and adapted to dispense with the usual collar button and enable a necktie to slide freely through the collar.

A further object of the invention is to provide a collar fastener of this character which when desired may be arranged out 25 of the way to enable the ordinary collar button to be used for fastening a collar to the shirt at the back thereof.

With these and other objects in view the invention consists in the construction 30 and novel combination and arrangement of parts hereinafter fully described, illustrated in the accompanying drawings and pointed out in the claim hereto appended, it being understood that various changes in the form, 35 proportion and minor details of construction may be resorted to without departing from the spirit or sacrificing any of the advantages of the invention.

In the drawing Figure 1 is a rear elevation 40 of a portion of a shirt provided with a collar fastener constructed in accordance with this invention, and shown in engagement with a portion of a collar, Fig. 2 is a vertical sectional view of the same. Figs. 3 45 and 4 are detail views of the members of the clasp.

Like numerals of reference designate corresponding parts in the several figures of the drawing.

50 In the accompanying drawing in which is illustrated the preferred embodiment of the invention, 1 designates a tab of substantially oblong form provided with a tapered lower or outer end 2 and secured at its other end 55 to the neck band 3 at the upper portion of the button hole 4 to enable it to be passed

through the same and pushed into the neck band when it is not desired to use the tab. The button hole 4 is formed in the loose outer ply or portion of the neck band and 60 when the tab is pushed into the button hole the latter is free for use and the tab hangs down in rear of the said loose ply or portion and is out of the way. This will enable an ordinary collar button to be used 65 when desired. The button hole 4 is formed in an outer ply or portion 5 of the neck band, the inner ply or portion 6 of the neck band of the shirt being designed to be interposed between the neck of the wearer 70 and a collar button when the same is used. The tab which is adapted to be passed through the button hole 7 of a collar 8 is provided at its outer portion with the female member 9 of a clasp composed of the 75 said female member and a male member 10. The female member comprises a flat relatively large circular plate secured relatively near and concentric with the rounded end 2 of the tab 1 and has a central opening 11 and provided thereat with a substantially annular wall 12 from which extends an inwardly projecting resilient annular flange. The inwardly projecting annular flange which is spaced from the outwardly projecting wall or flange 12 is split at intervals at 14 to enable it to expand and contract and engage the male member which consists of a plate or flange and a head 15 of circular form connected with the plate or flange by a neck portion 16. The clasp is shown on an enlarged scale in Fig. 2 of the drawing but in practice the male and female members will be constructed of thin sheet metal and will be made exceedingly 95 flat so as not to cause any material bulging of the parts.

The base plates or attaching portions of the male and female members of the clasp may be secured to the tab and to the shirt 100 by any suitable means such as stitching or the like and suitable perforations 17 and 18 are preferably provided for this purpose.

It will be seen that the device is exceedingly simple and inexpensive in construction, 105 that it is adapted to be readily applied to a shirt without necessitating any alteration in the construction thereof and that it is adapted to dispense with the ordinary collar button and enable a necktie to slide freely 110 through a collar without binding or catching at the back as is the case when an ordi-

2
nary collar button is employed. Also it will be clear that the tab may be pushed into the neck band out of the way should it be desired at any time to use an ordinary collar 5 button and as it is attached to the upper portion of the button hole it will not in any way interfere with such use. It is further evident that the positioning of the circular plate of the female member in relation to 10 the rounded end of the tab, will provide a stiffener for the tab and a means for facilitating the insertion of the tab through the bottom holes of the collar and collar band.

What is claimed is:—

- 15 The combination with a shirt having a neck band with a loose outer ply opened at the bottom and provided with a button hole, of a collar fastener including a tab secured at its upper end to the neck band 20 at the top of the button hole at the inner face of the loose outer ply and carried by the latter and adapted to be arranged between said loose outer ply and the neck band and to hang down out of the way in rear

of the free lower edge of said outer ply 25 portion, said tab being also adapted to be passed through the button hole of the loose outer ply and the button hole of the collar, the free end of said tab being rounded, a fastener for securing the free end of the 30 tab to the shirt below the neck band, said fastener comprising a male member having a head secured to said shirt below said neck band, and a female member having a socket and a flat relatively large circular flange 35 secured relatively near and concentric with said rounded end of said tab, whereby the flange of said female member acts as a stiffener and a means for inserting said tab through the button hole of the collar and 40 said loose ply.

In testimony whereof I affix my signature in presence of two witnesses.

EDWIN MILLER.
